APPARATUS FOR PRODUCING GAS

Norman Francis Pratt, St. Petersburg, Fla.

Application September 25, 1930, Serial No. 484,426

4 Claims. (Cl. 158—53)

This invention relates to structure and process for vaporizing hydro-carbon oils and other liquid fuels and other liquids in such a way that neither the liquids which are vaporized nor the vapors formed from them are broken down or changed chemically in any way and is to avoid the formation of carbon when vaporizing hydro-carbon oils for the purpose of supplying these vapors formed to substitute for fuel gas; in this connection an intermediate liquid whose boiling point is above that of water is used.

The prime object is to obtain oil-vapor for use from hydro-carbon oil by the quickest and most efficient means, wherein the fuel gradually vaporizes as it ascends in heat-interchangers and avoids ebullition which would impair the efficiency of the heating apparatus. Heretofore, where hydro-carbon oils are subjected to sudden heat, ebullition takes place which results in a mixture of vapor and liquid instead of a solid column of dry vapor, which is highly desirable for efficient burning, equalling or surpassing the result obtained from fuel gas. In my invention the oil is vaporized and held in a vaporous state until used, the range of temperature being above that of the dry point of the oil but below the cracking point of the vapor, the vapor having the qualities (in this range of temperature) of a mixture of fixed gases and throughout the specification is referred to as a gas.

Another object is to provide a series of heating elements, made of different metals, each having a different heat conductivity, whereby an element of quick conductivity can be used to start the vaporizing operation and one of slower conductivity utilized after the vaporizing operation is under way.

Another object is to utilize a substance (liquid) having its boiling point higher than that of water but below the cracking point of the hydro-carbon being vaporized, so that this high boiling liquid may be first vaporized by a prime heating element and its vapor brought through a heat-interchanger to in turn vaporize the hydro-carbon oil. The liquid has therefore a high boiling point and at a low and safe pressure has a temperature above the dry point of the oil but below the cracking point of the gas formed from the hydro-carbon. The vapor from the liquid is made to pass downward through a super-heater and heat-interchangers; through an adjacent passage the hydro-carbon and gas resulting therefrom are passed upward in the opposite direction.

In this way the gas from the hydro-carbon is

formed without ebullition and super-heated to a point just below its cracking point. It is impossible to form carbon under this process as the vapor from the intermediate liquid never reaches the temperature at which the oil-gas begins to crack but is always at a temperature above the dry point of the hydro-carbon being vaporized as it comes in contact with the walls of the super-heater and heat-interchanger, so that, as it passes downward it gradually gives off its heat to the rising hydro-carbon and gas and condenses where it gives off its latent heat and passes by gravity back to the boiler where it is re-vaporized to repeat the cycle.

Still another object is to do away with any other pressure than that resulting from gravity in the use of this apparatus. Since gas formed from the oil is so rich that at the common pressures of fuel-gas, it does not exert sufficient drag to pull in enough fresh air for complete combustion (blue-flame) means must be provided to dilute this rich oil-gas with air or some other gas or vapor so that the resultant gas stream will approximate the heat value of ordinary fuel gas at the ordinary and common pressure and will have the same heat value per cubic foot and exert the same pull in properly designed air-mixing devices. My arrangement makes possible the use of this apparatus without subjecting the oil to other than pressure produced by gravity.

Another object is to place in the system a mass of cheap metal which has slow conductivity but great thermal capacity. This mass is so proportioned that it ordinarily absorbs heat from chemical vapor or a heating element, so that the heat above the boiling point of the fuel and below the cracking point of the gas is sufficient in heat units to supply heat to vaporize fresh fuel until the chemical boiler can start delivering heat to a thin walled vaporizer or a vaporizer of greater conductivity and less thermal capacity.

Other objects will be disclosed in the specification and claims forming a part of this application.

In the drawings:

Figure 1 is a diagrammatic vertical section of the system showing the parts in relation to each other;

Figure 2 is a horizontal section taken on line 2—2 of Figure 1;

Figure 3 is a detailed section taken on line 3—3 of Figure 1;

Figure 4 is a vertical section of the valve shown in Figure 3, taken on line 4—4 of Figure 1;

Figure 5 is a detailed view in section of a

valve forming a part of the apparatus shown in Figure 1;

Figure 6 is a section on line 6-6 of Figure 5.

Figure 7 is an irregular section taken on line 5 7-7 of Figure 5;

Figure 8 is a section taken on line 8-8 of Figure 5; and

Figure 9 is a horizontal section taken on line 9-9 Figure 8.

10 Referring to the drawings in which like parts are designated with similar numerals:

Numeral 14 designates a boiler in which is placed a chemical, such as di-phenyl-oxide or other chemicals whose boiling points are higher 15 than that of water but lower than the cracking points of the hydro-carbon oils or other liquids being vaporized or of the vapors produced from these particular liquids.

Such chemicals will not break down under the 20 direct application of heat as applied to the boiler but will give off vapors which have relatively high temperatures and relatively low pressures. Beneath the boiler 14 is placed a source of heat 15. Extending from the boiler 14 is a duct 16 which passes through a vapor dryer 17, and in turn to other vaporizers (heat interchangers) 18, 19, 20 and 21. It is to be noted that the vapor dryer 17 is inclined so that any condensation passes back to the boiler 14 by way of 25 vaporizers 18, 19, 20 and 21 and away from duct 16, thus making it possible to retain all of the chemical vapor's heat for purposes of heating the oil and oil-gas in the dryer and vaporizers. Extending from duct 16 is a duct 22 in the form of 30 a header from which extend ducts 23 and 24 into vaporizer 19, duct 25 into vaporizer 20, and ducts 26 and 27 into vaporizer 21. The vapor dryer 17 is connected to the vaporizers 18, 19, 20, and 21 by ducts 28, 29, 30, and 31. Partial check 35 valves 32, 33, 34, and 35 are placed in ducts 28, 29, 30 and 31 respectively. Return vapor ducts 34a, 35a, 36, 37, 38 and 39 connect with header pipe 40 which connects with lower part of boiler 14. A reservoir 41 containing hydro-carbon oil 45 or other liquid to be vaporized without cracking, is placed in such a manner that its top or overflow is below top of lowest vaporizer but high enough to assure passage by gravity of the liquid through the system. Extending from the bottom 50 of the reservoir 41 is a pipe 42 having branches 43, 44, 45, and 46 leading therefrom, each of said branches in turn leading into bottom of vaporizers 18, 19, 20 and 21 respectively. The vaporizer 18 is, in the drawings, in the form of a jacket 55 and has extending therethrough the single pipe 16 which upon emerging from the vaporizer 18 as 36a forms the header pipe 40.

It is to be noted that only a small amount of space is contained in the vaporizer 18 as compared to the other vaporizers. Extending through the vaporizer 19 are the two ducts 23 and 24 (but which may be more if desired) which emerge from the vaporizer 19 as vapor ducts 35a and 36 to connect with the header pipe 40. Vaporizer 60 20 has a duct 47 with very thick walls 48 of iron or other slow conducting substance, the duct 47 connecting with inlet duct 25 and return vapor-condensate duct 37 which in turn connects with header pipe 40. Vaporizer 21 has ducts 49 and 50 (but which may be more) with thick walls 51 of iron or other slow conducting substance. These ducts 49 and 50 connect with inlet ducts 26 and 27, respectively, and outlet ducts 38 and 39 which in turn connect with header pipe 40. 70 75 The vapor ducts 41, 49 and 50 not only have walls

that are much thicker than the walls of pipe 16, 23 and 24 in the vaporizers 18 and 19, but the pipes 16, 23 and 24 may be of the thinnest material consistent with tightness and mechanical strength so as to make possible the most rapid 5 interchange of heat from the chemical vapor to the oil and oil-gas. Just before the branches 43 and 44 is placed a partial check valve 52, and just before branches 45 and 46 is placed a similar partial check valve 53. Figure 3 shows a horizontal section of check valve 52. The moving disc has a very small hole therein which permits a small quantity of liquid to flow through to the vaporizer but, in case of excessive pressure will immediately open to fullest extent to relieve pressure by permitting oil (liquid) and/or gas (vapor) 10 to push back toward reservoir 41. 53 operates in a similar manner. Thus no excessive pressure 15 may form in the oil and gas ducts.

In duct 16 just before it enters vapor dryer 17, 20 is a pressure indicator 54 and also a safety valve or fitting 54a to protect the system against excessive pressure. Leading from the vapor dryer 17 is a pipe 55 which in turn leads to diluting valve 56 at pipe connection 61. Valve 56 is supported by clamp 57 and has a nozzle 58 which is similar to the nozzle of an ordinary gas-cock on a gas stove, this nozzle may connect to any suitable device for mixing gas and air such as in a Bunsen burner or on an ordinary stove or range. In pipe 55 is a constricted passage 72 so constructed that it will only pass the maximum of oil-gas for which the apparatus is designed and thus serves to prevent damping of heat of the vaporizers by overload. The entire system comprising the chemical-boiler, duct 16, return header 40 and all intermediate digressions, ducts, fittings, etc. are to be made tight and with no openings to either liquid or gasses or to the outside air as it is the intention to use the chemical 40 over and over again without wastage. All parts subject to heat radiation other than through heat interchangers and vapor dryers are to be thoroughly heat insulated wherever practicable to do so. Figure 4 shows a vertical section of 45 partial check valve 34 which is so designed with a small opening in the closer that it permits the free upward flow of gas or liquid but a very slow return. This is the same with 32, 33, and also 35. As shown in Figure 5 the inside of the 50 valve 56 is machined out concentrically, so as to receive a valve-core 60, as shown in Fig. 7, which fits the valve intimately where the valve-ports 66, and 67 are located. The inner section of the 55 valve core 60 is machined out sufficient to permit gasses which pass through any of the ports to enter a common chamber and so mix.

The oil-gas produced from the apparatus is so rich in heat units that it cannot be used efficiently 60 if taken at the same pressure as fuel gas. It must be diluted to approximately the same heat value per cubic foot as fuel gas. This is accomplished by the diluting valve shown in Figure 5. Rich oil-gas is brought from pipe 55 (Fig. 1) to valve 65 through duct 61. Air, or a lean or inert gas or mixture of gases or even steam, under approximately the same temperature and pressure, is brought to the other fitting 95 of the diluting valve. From the point of heating unto and including the diluting valve the entire system is 70 thoroughly heat insulated. Yoke 62 is fixed to the stem 63 of the core 60. An eccentric or cam 65, as shown in Figures 8 and 9, is connected to the yoke 62 to bring the core 60 which has passages 66 into alignment with passages 67. These 75

passages are spaced along a common normal circle of the figure formed by the inside surface of the diluting valve 56 and are of the same diameter. The object being to give a fixed (never variable) proportion of rich gas and diluting gas at any opening of the ports. The volume only of the mixture varies with the opening—the proportion remains the same. The gas from the lower port passes in the chamber formed by the core 60 and 10 mixes with the incoming gasses from the upper ports. This mixture passes down through the nozzle and out at opening near 58. This mixture has approximately the same richness and velocity as fuel gas. The nozzle 58 is attached to the 15 body 56 in such a way as to have a gas-tight joint and is shaped to avoid the formation of a pocket which could catch condensation. The area of the opening in the nozzle 58 may be changed so as to have a larger or smaller opening but 20 under no conditions would the cross-sectional opening of the nozzle 58 be less in area than the combined effective areas of the ports when in nearest alignment.

Interchange of eccentric 65 for one of greater 25 or less eccentricity with same diameter permits regulation of maximum effective alignment of ports. In this way the same diluting valve may be used from the very smallest use, such as simmering flame under a coffee percolator to a maximum as used in the largest hotel or restaurant gas-ranges. The only change necessary would be to change the nozzle 58 and the eccentric 65 to correspond. A coil spring 68 holds the core 60 in gas-tight contact with the body 58.

As actually operated, the reservoir 41, having therein the liquid to be vaporized (hydro-carbon oil) and this liquid having descended through pipe 42 through the various branches 43, 44, 45 and 46 and entered the vaporizers 18, 19, 20 and 40 21 to a height commensurate with the height of the reservoir 41 and the volume of the liquid contained therein, and other laws of nature that cover such conditions, there will be a substantial amount of hydro-carbon liquid in the various 45 vaporizers.

A chemical, such as diphenyl-oxide, having a boiling point above that of water but lower than the cracking point of the hydro-carbon is placed in the boiler 14, and a source of heat 15, which 50 may be either gas burner or an electric heating element, or any other suitable heating device, is operated to heat the chemical in the boiler. As the chemical becomes heated vapor from the chemical rises in duct 16 and enters a vapor dryer 55 17 and continues through the vapor dryer 17, passing freely through ducts 22, 23, 24, 47, 49 and 50 which lead from ducts 16, which in turn passes through vaporizer 18 to the header pipe 40 and then back to the boiler 14. Return ducts 35a, 36, 60 37, 38, and 39 leading from ducts 23, 24, 47, 49, 50 after passing through their respective vaporizers also connect with header pipe 40 and return condenser chemical vapor to the boiler 14.

In order to prevent undue pressure on the 65 chemical boiler system or undue temperature due to excessive pressure, which might cause the generated gas to crack or change chemically, a pressurestat 73 is inserted in the boiler system. When the pressure of the chemical in the boiler system 70 reaches a predetermined point the pressurestat operates to temporarily discontinue or reduce the heating action of the boiler heater. When the pressure drops to another pre-determined point the device operates to recommence or increase 75 the heating action under the boiler. It is to be

carefully noted that the vapor from the chemical boiler 14 will be on the inside of the hydro-carbon fuel and, as the vapor passes through the ducts in the vaporizers, heat will be given off through the walls of the ducts and the vapor chambers, thus heating the hydro-carbon fuel. It is also to be carefully noted that heat from vapor from chemical boiler is most intense at highest point of gas-dryer 17 and that vaporizing of the fuel from reservoir 41 is done in the vaporizers from the top downward. Also it is to be noted that due to the pitch of the ducts from the chemical boiler from the point where the first condensation may commence, that is at the top of the gas-dryer, the condensed chemical must pass by gravity down into and it must build up slightly in ducts 34a, 35a, 36, 37, 38, and 39 and form a top level above that of the liquid chemical in the boiler 14 and thus by hydrostatic pressure force vapor from boiler 14 upward through pipe 16 and likewise 10 condense liquid through header 40 into boiler 14 at the bottom. Since it is highly desirable, under certain circumstances, to obtain a supply of gas immediately, the duct 16 passing through vaporizer 18, has thin walls and may be of the thinnest material consistent with tightness and mechanical strength, so as to induce rapid transfer of heat.

The vaporizer 18 likewise has a small capacity of volume so that the heat passing through the 30 walls of the duct 16, will rapidly permeate the hydro-carbon fuel in the vaporizer 18 and quickly reduce the fuel to a gaseous state. Vaporizer 19 is likewise designed to generate gas quickly and has practically the same construction as 18 except that it contains a multiplicity of thin-walled ducts 23 and 24 and has greater cubical content than vaporizer 18. Instead of having thin walls of quick conducting material the walls 48 of vapor duct 47 in vaporizer 20 are of thick material, such as iron, and massive so as to afford a reservoir for storing up heat and a slow conductivity so that it may be arranged to give up its heat slowly on demand. The same is true of vaporizing ducts 49 and 50 in vaporizer 21 which 35 indicates a vaporizer having a multiplicity of 40 ducts. The most important function of the heavy walls of the ducts in 20 and in 21 is to store up heat and to supply heat for gas during 45 outings in which the heating effect under the chemical boiler is either reduced or else cut off entirely. Also in that interval between the application of heat to the chemical boiler 14 and the time when the vapor applies its heat to the thin walled vaporizers 18 and 19 the heavy walled 50 tubes will give out part of their heat to vaporize 55 the fuel. The efficient heat insulation mentioned will reduce radiation losses to a minimum. After the hydro-carbon fuel has become sufficiently heated to assume the gaseous state, the gas will 60 ascend in the several ducts, pass through dryer 17, where it attains a temperature approximately that of vapor from chemical boiler 14, thence out through pipe 55, through constricted passage 72 and to opening 61 in diluting valve 56. There 65 is one diluting valve for each gas jet. Operation of handle 71 (see Figure 8) which rotates in a support 57a which is rigid with 57 (see Figure 6) and which rotates an eccentric within yoke 62 causes valve-stem 63 to rotate bringing ports 66 70 in valve core 60 in proportionate alignment with ports 67 in valve-body 56.

By this simple mechanism an exceedingly fine adjustment of effective openings 70 may be obtained without using unusual care in moving the 75

handle 71. The object being to simulate as nearly as possible the movement of an ordinary fuel-gas cock on an ordinary gas range.

It is obvious that my invention may be used in other forms than those used to illustrate it in my drawings, and I do not intend to limit myself to the particular forms shown, but claim as my invention any apparatus utilizing the principles of my invention in conformity with the claims 10 appended hereto.

What I claim is:

1. An apparatus for vaporizing liquid fuel without cracking, comprising a plurality of vaporizers, each vaporizer having fuel and vapor compartments, the fuel compartment in each vaporizer surrounding each vapor compartment, the outer wall of said vapor compartment and the inner wall of said fuel compartment forming a common wall conducting heat from said vapor to said fuel, the common wall of one of said vaporizers being thinner and of better conductive material than the material forming the common wall of the other vaporizers.
2. An apparatus for vaporizing liquid fuel without cracking, comprising a liquid fuel tank, a plurality of vaporizers, each of said vaporizers having fuel and vapor compartments separated by a wall of heat conducting material valve controlled means connecting said tank to the fuel compartment in each vaporizer, the common wall of one of said vaporizers being thinner and of better heat conducting material than the common wall of others of said vaporizers.

3. An apparatus for vaporizing liquid fuel without cracking, comprising a fuel tank and a vapor producing receptacle, a plurality of vaporizers, each vaporizer having fuel and vapor compartments separated by a common wall of heat conducting material, means for connecting said fuel and vapor compartments to the fuel tank and vapor producing receptacle, respectively, the common wall of one of said vaporizers being formed of material of greater heat conductivity than the common wall in the other vaporizers, and means for returning the vapor in condensed form from all of the said vapor compartments to the vapor producing receptacle, and means for conveying gas from all of the fuel compartments in said vaporizers.

4. An apparatus for vaporizing liquid fuel without cracking, comprising a fuel tank and a vapor producing receptacle, a plurality of vaporizers, each vaporizer having fuel and vapor compartments separated by a common wall of heat conducting material, means for connecting said fuel and vapor compartments to the fuel tank and vapor producing receptacle, respectively, the common wall of one of said vaporizers being thinner and composed of material of greater heat conductivity than the corresponding wall in the other vaporizers, means for returning the vapor in condensed form from all of said vapor compartments to the vapor producing receptacle, and means for conveying gas from the fuel compartments of said vaporizers.

NORMAN FRANCIS PRATT.
